HAND SUPPORTABLE CLAMP AND BENCH
MOUNT THEREFOR

Foy E. Bellows, Dallas, Tex.

Application March 26, 1951, Serial No. 217,419

3 Claims. (Cl. 81—21)

1

This invention relates to clamping devices and more particularly to clamping devices which may be held in the hand or be rigidly secured to a fixed structure.

In the setting of precious stones in rings, or other jewelry, the ring must be held rigidly in some type of clamping device during filing, sawing and shaping of the setting. The clamping device must be capable of a large range of adjustment so that all portions of the setting may be made readily accessible to the working tool such as a file or graver. It is possible to employ clamping devices which are held in the hand but the hand does not provide as rigid a support as is necessary for some operations. In such operations the tool employed often slips and injures the hand holding the clamping device. It is desirable, therefore, to have a clamping device in which a ring or other object can be secured rigidly, quickly and easily. Moreover, the clamping device should be small enough to be held comfortably in the hand and also be capable of being secured rigidly to a bench or other fixed structure in any one of various adjustable positions so that all surfaces of the object on which work is to be done can be easily made accessible to the working tool.

Accordingly, it is an object of this invention to provide a new and improved clamping device.

It is another object of this invention to provide a new and improved clamping device which may be held in the hand or may be easily secured to a fixed structure in any desired position.

It is still another object of this invention to provide a new and improved clamping device in which an object may be secured rigidly, quickly and easily.

In brief, the new and improved clamping device includes a vise having at one end a plurality of jaws between, and by which, an object may be held rigidly. The jaws are forced toward each other by the camming action between link members which pivotally secure the jaws to a common post and an annular member into which the common post is screwed. A handle is disposed on the other end of the vise and a substantially spherical body is disposed between the jaws and the handle. The spherical body may be clamped to a plate in any desired position by means of a screw operated slidably insert. The plate in turn can be rigidly secured to a bench or other fixed table by a C-shaped clamp whose upper end may be made in the form of an anvil.

For a better understanding of the invention, reference may be had to the following description taken in connection with the accompanying drawing and its scope will be pointed out in the appended claims.

In the drawing,

Figure 1 is a perspective view of the clamping device secured to a bench;

2

Figure 2 is a side view of the clamping device shown in Figure 1;

Figure 3 is a sectional view of a portion of the device illustrated in Figures 1 and 2 with the jaws shown in open position;

Figure 4 is a sectional view of a portion of the device illustrated in Figures 1 and 2 with the jaws shown in closed position;

Figure 5 is a top plan view of a modified form 10 of the jaws shown in Figures 1 to 4;

Figure 6 is a perspective view of the links and post of the jaws shown in Figure 5; and,

Figure 7 is a perspective exploded view of two components of the device.

Referring now especially to Figures 1 to 4 of the drawing, a vise 10 is shown clamped to a plate 11 which in turn is clamped to a bench 12. The vise 10 has a pair of opposed jaws 12 and 13 which are pivotally secured to a common post 14 by links 15 and 16, respectively. The substantially L-shaped links 15 and 16 have substantially vertical legs 17 and 18, respectively, which extend into slots 19 and 20 in the jaws 12 and 13 and which are pivotally secured to the jaws 12 and 13 by pins 21 and 22, respectively. Substantially horizontal legs 23 and 24 of links 15 and 16, respectively, are disposed in a slot provided in the upper end of the post 14 and are pivotally secured to the post by a pin 25.

30 The post 14 has a reduced shank 26 which is threaded and extends into the threaded bore 26' provided in the central portion 27 of the vise 10. The central body portion consists of a substantially spherical body or ball 28 on which is disposed a cup shaped camming body 29 formed by a recess 30 to receive the top portion of the post 14 and by a rim 31 to contact the legs 23 and 24 of the links as the post is screwed into the bore 26'. It will be apparent that as the post

35 is screwed into the bore, the links will be pivoted inwardly by the camming action of the rim 31 causing the jaws 12 and 13 to approach each other. Any object inserted between the faces 32 and 33 of the jaws 12 and 13 can thus be rigidly gripped by the jaws by rotating the jaws in a clockwise manner. The faces 32 and 33 are preferably made of leather, fibrous material, or other yielding substance to prevent marring of the surface of the object held between the jaws.

40 The ball 28 is provided with a threaded bore into which is screwed the threaded end 34 of a handle. The vise 10 may be held in one hand while the object held between the jaws is worked on by a tool held in the other hand. In many cases, the hand cannot support the vise firmly enough for

45 the operation which is to be performed on the object held between the jaws. In this latter case, the vise may be clamped to the plate 11 in any desired position.

50 The plate 11 is provided with an aperture 35 through which slidably extends the vertical portion 36 of a C-shaped clamp 37. The upper portion of the clamp 37 may be formed in the shape

of an anvil 38 and is rigidly secured, as by welding, to the portion 36 after the latter has been inserted through the aperture 35. The clamp 37 also includes a screw 39 which passes through a vertical threaded bore in an end 43 of the clamp. The plate 11 can therefore be rigidly secured to the bench 12 by placing the anvil 38 and the plate 11 on opposite sides of the bench and rotating the screw 39 to draw the plate and anvil toward each other.

The end of plate 11 remote from the clamp 37 is provided with an arcuate concave recess 41 which fits the convex surface of ball 28. An end piece 42 has a pair of parallel legs 43 and 44 whose ends abut the end of the plate 11 on the opposite sides of the concave recess 41. The end piece 42 is rigidly but detachably secured to the plate 11 by a pair of screws 45 and 46 which extend through holes in the legs 43 and 44, respectively, to engage in registering threaded bores in the end of plate 11. The holes in the end piece are enlarged as at 47 to provide abutments against which the heads of screws 45 and 46 can bear.

The inner sides of the legs 43 and 44 are grooved as at 48 and 49, respectively, to receive the outwardly projecting tongues 50 and 51 provided on opposite sides of an insert 52. The insert 52 is also provided with an arcuate concave recess 53 which fits the convex surface of ball 28. The insert 52 is so positioned that the two recesses 41 and 53 face each other and contact opposite portions of ball 28. A thumb-screw 54 engages in a threaded aperture 55 in end piece 42 and its end bears against the back side of the insert 52 so that by rotation of the thumb-screw the insert can be moved toward the plate 11. Since the ball 28 is positioned between the insert 52 and the plate 11, the ball 28 may be locked in any desired position by rotating the thumb screw to move the insert against the ball.

The manner in which the vise 10 may be adjusted when secured to plate 11 will now be obvious. If the vise 10 must be moved frequently, the thumb-screw 54 is rotated to a position in which the ball 28 may be rotated more or less freely between the insert and the plate. The handle 35 is grasped in one hand and a tool in the other. It will now be possible to move the vise into innumerable positions since the manner in which the ball 28 is mounted will allow rotary movement of the ball in any direction. The vise, however, is held firmly by the plate 11 so that a relatively firm support is provided for the vise. Slippage of tools off the object held between the jaws 12 and 13 will therefore be minimized.

If a very rigid support is required, the vise is moved to the desired position and the thumb-screw is rotated to lock the ball 28 between the insert 52 and the plate 11 and hold the vise immovable.

Figures 5 and 6 illustrate a modified form of the jaw assembly shown in Figures 1 to 4. The jaw assembly 56 includes three jaws 57, 58 and 59 which are pivotally secured to a common post 60 by links 61, 62 and 63, respectively. The L-shaped links 61, 62 and 63 have ends pivotally secured to the common post by suitable pins and disposed in slots 64, 65 and 66, respectively, of the common post. The opposite upper ends of the links 61, 62 and 63 are disposed in slots 67, 68 and 69 of the jaws 57, 58 and 59, respectively and are pivotally secured to the jaws by suitable pins. The jaws shown in Figure 5 will operate in a similar manner as the jaws shown in Figures

1 to 4 to hold an object between them when the post 60 is screwed into the bore 26.

It will be seen now that a clamping device has been illustrated and described which provides a vise in which an object can be quickly and easily clamped. Furthermore, the vise described can be held in the hand or can be clamped to a fixed plate in any desired position by movement of the handle and rotation of the thumb-screw 54.

It will be apparent that various changes and modifications can be made in the described and illustrated embodiments of the invention without departing from the invention and it is intended, therefore, in the appended claims to cover all such changes and modifications as fall within the true spirit and scope of the invention.

What is claimed is:

1. In a clamping device, the combination comprising a horizontal mounting plate having one end anchored and provided at its opposite end with a semi-circular recess, a substantially U-shaped end piece, whose legs are attached to the end of said plate on opposite sides of said recess, an insert slidably disposed between the legs of said end piece and having a semi-circular recess therein opposing the recess in said plate to define jointly with the latter a circular opening having concave walls, a ball rotatable in said opening, a screw threaded through said end piece for moving said insert in relation to said ball to hold the same in adjusted positions, a handle attached to said ball below said plate, clamping jaws carried by said ball above said plate and means for moving said jaws into and out of clamping engagement with work between said jaws.

2. In a clamping device, the combination comprising a horizontal plate adapted to be affixed at one end to a support, a U-shaped end piece attached to the opposite end of said plate and having confronting grooves in its legs, an insert between the legs of said end piece and having tongues slidably in the grooves of said legs, said insert having a semi-circular recess confronting a recess of like formation in said opposite end of said plate, said recesses jointly defining a circular opening having concave walls, a ball retained in said opening, means for manipulating said ball to a variety of positions, means bearing against said insert to frictionally hold said ball in adjusted positions and work clamping means carried by said ball opposite said manipulating means.

3. The structure of claim 2; said clamping means comprising a cup-shaped camming body integral with said ball, a vertical shank threaded axially through said camming body and into said ball, a series of substantially L-shaped links whose horizontal portions are pivoted at their ends radially about the upper end of said shank, a plurality of complementary jaws pivoted to the upper ends of the vertical portions of said links and adapted to be moved in relation to each other by engagement and disengagement of the angles of said links with said camming body through rotation of said shank.
